Primary Examiner — Barbara Fox*Assistant Examiner* — Dana K Weiland(74) *Attorney, Agent, or Firm* — NSIP Law**CLAIM**

The ornamental design for a display screen or portion thereof with icon, as shown and described.

DESCRIPTION

The sole FIGURE is a front view of a display screen or portion thereof with icon, showing my new design.

The dot-dash broken line in the FIGURE is included for the purpose of showing a display screen or portion thereof and forms no part of the claimed design.
